(54) **STOVES, FOR CARRIAGES**

(76) Inventor: **Alexander McWilliams**

Alexander Williams, Washington, D. C.

Letters Patent.

The schedule referred to in these Letters Patent and making part of the same, containing a description in the words of the said Alexander Williams himself of his improvement in the stove for heating carriages and other travelling vehicles.

To all whom it may concern be it known that, Alexander Williams, of the city of Washington, in the District of Columbia have invented an improvement in the stove for heating carriages and other travelling vehicles, for which Letters Patent of the United States were originally granted to me bearing date the twenty-sixth day of December eighteen hundred and thirty-two. And I do hereby declare that the following is a full and exact description thereof, with my said improvement.

I make a small stove for containing fuel, preferring charcoal for this purpose, although charcoal, or other coal, may be employed. The stove may be square cylindrical, or otherwise as may be preferred, and should vary in its dimensions according to the size or character of the carriage, or other vehicle, to be warmed. For a carriage of the ordinary size, when the cylindrical form is preferred, I have found one of sheet iron, or other metal, five inches in diameter, and five inches in height to be large enough to contain fuel sufficient for the consumption of four hours, producing during the whole time a general warmth.

The cylinder is shown at B, fig. 1, in the accompanying drawing, it stands vertically on the bottom of the carriage, and, generally, in the center thereof. The bottom of the cylinder is of sheet iron, or other metal, and an air pipe, or tube, C, extends from it through the

bottom of the carriage to admit a draught to the fire. This pipe or tube, may be six inches long, and either round, or square; but however, to make it quadrangular, and measuring about three inches by one inch and a half. One of its flat sides is perforated with holes at its lower end to admit air, and this side is turned towards the front of the carriage. For railroad cars, the cylinder B should be about twelve inches high, and ten in diameter. The air pipe, C, six inches long, eight wide and three deep. The fire is not to be put immediately into the above described cylinders but into one contained within it, which, for the size of stove first described, should be about four inches and a half in diameter, and four in height, having gates at its lower end; a space of four inches of an inch is left between the two cylinders, and an inch between their lower ends, which prevents the outer cylinder from being overheated. A top, or cover, is fitted on to the upper end of the stove, which cover, also, I make double, with a wide space between the two parts. A smoke, or chimney, pipe, A, passes through the middle of the top, say of about one and a quarter inch in diameter, in rail road cars. This pipe may be continued up and pass through the top of the car, but in carriages it should be bent twice at right angles, so as to turn down along side the stove, and pass through the bottom of the carriage.

When this stove is made square, as it is represented in the drawing, Fig. 2, its dimensions may be deduced from with the space of its capacity in the cylinder equal for all. It may be made in the form of a flat box, not more than five inches from the bottom of the carriage, so that the top may be placed upon it. The top may, in this case, be made to slide, or be hinged, and secured down by thumb screws, readily removable when fuel is to be supplied. See fig. 3 is the air pipe, or tube, B, the ash pit, which may be dispensed with, as the air pipe will answer this purpose.

C. the body of the stove. D. the door, or cover & screws for fastening it, and E. the smoke, or draught, pipe.

Instead of making the stove of double sheet iron, it may be made single, but then it should be lined with some imperfect conductor of heat; or instead of this the inner cylinder, or core, may be of cast iron. Instead of coal, lamps for burning oil, or any of the suitable spirituous compounds, may be employed, but I do not think these so convenient or so economical as charcoal. Having thus fully described my said invention and the improvement made thereon, I do hereby declare that although I have selected in this instrument of writing a description of the machine as originally constructed by me, I have done so for the purpose merely of showing how my present improvement is connected therewith, and that all which I now claim as constituting the said improvement, is the addition to my carriage stove of a tube, or pipe, for discharging the air which has passed through the fire, either under the body of the carriage by connecting the said pipe on by carrying it out through the top, or other part of the carriage, substantially in the manner herein set forth.
